(57) **CLAIM**

The ornamental design for a vent ring, as shown and described.

DESCRIPTION

FIG. 1 is a front view of a vent ring showing my new design; FIG. 2 is a front and left side perspective view thereof; FIG. 3 is a rear and left side perspective view thereof; FIG. 4 is a right side view thereof; FIG. 5 is a left side view thereof; FIG. 6 is a rear view thereof; FIG. 7 is a top view thereof; and, FIG. 8 is a bottom view thereof.

The broken lines and the de-emphasized areas within broken line depict portions of the vent ring that form no part of the claimed design.
